UNITED STATES PATENT OFFICE

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA

APPARATUS FOR MOLDING CAST IRON PIPES AND THE LIKE

Original application filed March 19, 1928, Serial No. 262,683. Divided and this application filed March 18, 1930. Serial No. 436,751.

This invention relates to apparatus which is advantageously used for molding long cast iron pipes, although capable of other uses, and, among other objects, aims to provide an improved pattern plate and improved flask sections co-operating therewith to expedite making multiple molds. The apparatus is preferably employed in connection with the system described and claimed in my co-pending application, Serial No. 220,731, filed September 20, 1927, now Patent No. 1,808,366, dated June 2, 1931.

This application is a division of my co-pending application, Serial No. 262,683, filed March 19, 1928, now Patent No. 1,765,021, dated June 17, 1930.

Referring to the accompanying drawings of a preferred form of the invention:—

Fig. 1 is a top plan view of the drag section of a flask;

Fig. 2 is an elevation of a portion of a jolt rammer with the pattern plate thereon, the patterns being in section, and a flask section shown above the pattern plate in cross section and ready to be rammed;

Fig. 3 is a fragmentary top plan view, on an enlarged scale, of the preferred means for holding the pattern plate and flask sections together;

Fig. 4 is a perspective view of the wedge, forming part of the holding means of Fig. 3;

Fig. 5 is a fragmentary side elevation, also on an enlarged scale, of the holding means of Fig. 3;

Fig. 6 is a fragmentary sectional view of one end of the pattern plate showing a guide pin for a flask section.

In the manufacture of cast iron pipe in horizontal molds, by what is known as the green sand process, the practice heretofore has been to use a molding machine having a stripping plate and drop pattern. One section of the flask is rammed at a time, and the rammed sections are removed and matched together with the core bar or bars between them.

There are some objections to the use of these stripping plates and drop patterns, the principal objection being that, in the course of time, the patterns and stripping plates

both wear and it is then quite difficult to keep them properly adjusted. Moreover, the mechanism of the drop pattern will not withstand rough usage to which it would be subjected if placed on a jolt rammer. Therefore, when employing the system heretofore in use, it has been necessary to ram the flasks by hand, which is laborious, expensive, and slow.

To speed up production and to economize in the manufacture of cast iron pipes and the like, it is highly desirable to employ the jolt ramming machines. To use this ramming apparatus successfully, it is necessary to employ "pattern plates" or "match plates". Such pattern plates have one-half of the patterns fastened to them and are made so as to permit lifting the flask sections off them after the jolt ramming. In the process of molding, each pattern plate in one operation forms one-half of one or more pipe molds and these halves (the flask sections) are subsequently matched together, with the cores properly placed in the molding space to make the complete mold.

In the manufacture of long cast iron pipe, the long flask sections are subjected to lateral and longitudinal displacement relative to the pattern plates and this also results in destruction of or serious injury to the molds. Hence, it is highly desirable positively to hold the flask sections between their ends to the pattern plate, and by holding means such as are capable of being used when the flask sections become warped or permanently deformed.

Referring specifically to the drawings, there is shown in Fig. 1 a drag section 10 of a multiple pipe flask designed to be employed in conjunction with a pattern plate, the drag shown also typifying the construction of the cope, which is not shown. Herein, the drag section is shown as having provision for molding four long sections of pipe at one time although it is to be distinctly understood that any convenient number of pipe sections may be made, within the mechanical limits of the apparatus. The drag shown is generally rectangular in outline and has a single pair of axially aligned trunnions 11 arranged

on its longitudinal axis and projecting from the end walls 12 so that the drag may be picked up by an overhead crane or carrier and conveyed about the plant. The illustrative drag is shown as having a plurality of reinforcing members 13 and 14 extending both longitudinally and transversely of the drag to strengthen the same so as to avoid undue deflection when picked up by the crane, 10 which would destroy the rammed molds. The specific construction and arrangement of these reinforcing members and other parts of the flask are described and claimed in the parent application Serial No. 262,683, so that 15 the above general description of the flask section will suffice.

Referring to Fig. 2, the drag section is shown applied to a pattern plate 15 on the surface of which is secured a plurality of 20 half pipe patterns 16. The pattern plate is preferably approximately the same width as the flask sections 10. To guide the flask section on the pattern plate and to prevent relative longitudinal displacement, as well as lateral displacement at the ends thereof, tapered guide pins 17 (Fig. 6) are provided at diagonally opposite corners of the pattern plate 15 and co-operate with bushed holes or openings 18 in the flask section (Fig. 1). One of the 25 holes is shown as being substantially elliptical so that it will receive its pin notwithstanding slight variations in length of the flask section, due to expansion or contraction. The pin, however, cannot move laterally or 30 longitudinally in the elliptical hole 18, when the other pin is in its hole.

To hold the flask section intermediately to the pattern plate, a pair of opposed brackets 19 (Figs. 2, 3 and 5) are shown as being bolted 35 to the sides of the pattern plate 15 and have overhanging portions for receiving holding wedges 20 between opposed, compound tapered faces 21 thereon and the vertical plane faces 22 of co-acting bosses or 40 pads 23 on the side walls 24 of the flask section 10. The taper of the wedges is both longitudinal and transverse (Fig. 4) so that when the wedges are inserted between the wedge-receiving faces, their thickest portions 45 at the bottom rest against a suitable shoulder 50 on the brackets whereby they tighten themselves automatically when the jolt rammer 26 is reciprocated up and down. The described wedge means will engage and hold 55 slightly warped flask sections. Moreover, the arrangement is such that the plane faces of the wedges which engage the bosses or pads 23 are also vertical and act as lateral guides for the flasks when they are being 60 lifted from the pattern plate, thus preventing rattling. After the flask section is thus immovably secured on the pattern plate, it is supplied with green sand and the jolt rammer 26 is operated. The section is jolted until the sand is well rammed; then the ram-

ming operation is completed by manually controlled pneumatic rammers.

To permit the flask sections to be removed from the pattern plate without destroying any part of the mold or without "rattling", 70 the patterns 16 (Figs. 2 and 7) are shown as being flattened or cut away adjacent to their junctions with the surface of the pattern plate. If the pattern were not cut away there would be a portion of its surface adjacent to the junction with the pattern plate which would be substantially vertical. Hence, there would not be sufficient draft for the patterns to permit the flask sections to be removed without destroying the molds. 75 Herein, the patterns have planed surfaces 27 extending upwardly at an angle of a few degrees from their junctions with the pattern plate to afford ample draft. I have found by many hundreds of trials that it is only necessary to cut away a few thousandths of an inch of the thickness of the pattern to provide this draft. Figs. 2 and 7 greatly exaggerate the flattened surfaces of the patterns so as to make them apparent. This 80 feature of the invention is described and claimed in an application which is another division of the above-identified parent application. 85

From the foregoing description, it will be seen that the improved apparatus here described permits rapid preparation of pipe molds and the like practically entirely by mechanical means. There are no parts of the patterns or flask sections which can be 90 distorted during the ramming operation. The apparatus makes practically perfect molds and will therefore permit the manufacture of long sections of pipes having thinner walls than could be produced by old methods. 100

Obviously, the present invention is not restricted to the particular embodiment thereof herein shown and described. Moreover, it is not indispensable that all the features of the invention be used conjointly, 110 since they may be employed advantageously in various combinations and sub-combinations.

What I claim is:

1. Apparatus for molding long castings comprising, in combination, a pattern plate having an elongated pattern part secured thereto; a flask section adapted to be placed on the pattern plate; means to prevent longitudinal displacement of the flask section on the pattern plate and lateral displacement at the ends thereof; and self-tightening wedges driven between and co-operating with the pattern plate and flask section intermediate the ends thereof and on opposite sides of the flask section to prevent relative lateral displacement. 120

2. Apparatus for molding long castings comprising, in combination, a pattern plate 130

having an elongated pattern part secured thereto; a flask section adapted to be placed on the pattern plate; means to prevent longitudinal displacement of the flask section on the pattern plate; and wedge means engaging the flask section and the pattern plate on opposite sides to prevent relative lateral movement and separation.

3. Apparatus for molding long castings comprising, in combination, a pattern plate having an elongated pattern part secured thereto; a flask section adapted to be placed on the pattern plate; means to prevent longitudinal displacement of the flask section on the pattern plate and lateral displacement at the ends thereof; a pair of wedge members engaging opposed faces adjacent to the side edges of said flask section and pattern plates about midway between their ends, said 20 wedges adapted to engage slightly warped flask sections.

4. Apparatus for molding long castings comprising, in combination, a pattern plate having an elongated pattern part secured thereto; a flask section adapted to be placed on the pattern plate; means to prevent longitudinal displacement of the flask section on the pattern plate and lateral displacement at the ends thereof; and wedges which taper 30 both longitudinally and laterally co-operate with complimentary surfaces on the pattern plate and flask section intermediate the ends thereof and on opposite sides of the flask section to prevent relative lateral displacement.

5. Apparatus for molding long castings comprising, in combination, a pattern plate having an elongated pattern part secured thereto; a flask section adapted to be placed 40 on the pattern plate; tapered guide pins at diagonally opposite corners of the pattern plate co-operating with corresponding openings in the flask section to prevent longitudinal displacement of the flask section on the pattern plate; one of said pins fitting its hole snugly, so that movement is obviated; the other hole being elliptical, and the pin being in contact with the two sides but not the ends, so that expansion and contraction does not 50 prevent registry of both pins with their holes, while lateral displacement at the ends is eliminated.

6. In combination with a flask section and pattern plate for molding long castings and the like, pairs of opposed, wedge-engaging surfaces on opposite sides of the flask section and pattern plate, and a pair of wedges adapted to be driven longitudinally of the flask section to be tightened between the opposed surfaces to prevent relative lateral displacement.

7. In combination with a flask section and pattern plate for molding long castings, pairs of opposed wedge-receiving faces on 65 opposite sides of the pattern plate and flask

section; and self-tightening wedges between said faces to prevent relative lateral displacement of the flask section and pattern plate.

8. In combination with a flask section and pattern plate for molding long castings, pairs of opposed wedge-receiving faces on opposite sides of the pattern plate and flask section; and wedges tapered both laterally and longitudinally adapted to be driven between said wedge-receiving faces to prevent relative lateral displacement of the flask section and pattern plate.

9. A pattern plate and flask section for molding long castings comprising, in combination, guide pins at the ends of the pattern plate to prevent longitudinal displacement relative to the flask section; co-operating wedge guiding and receiving surfaces on the opposite sides of the pattern plate and flask section; and wedges inserted between said guiding and receiving surfaces to prevent relative lateral displacement of the pattern plate and flask section.

10. A pattern plate for the molding of cast iron pipes or other elongated castings provided with a guide pin at each end for properly matching the flask sections therewith; and central, lateral guides consisting of a bracket on each side having an inner surface adapted to engage with a wedge on the opposite side thereof.

11. A pattern plate for the molding of cast iron pipes or other elongated castings provided with a guide pin at each end for properly matching the flask sections therewith; and central, lateral guides consisting of a bracket on either side adapted to engage a wedge on the outside thereof; said guides being tapered both horizontally from end to end and vertically from bottom to top to prevent loosening of the wedges during the ramming process.

12. In combination with a pattern plate and flask section for pipe molds, wedge means driven between complementary surfaces on the pattern plate and flask section to hold the flask section against lateral displacement on the pattern plate, said wedges presenting inner vertical guiding surfaces for the flask section to insure a perfect "lift" without "ratting".

13. In combination with a pattern plate and flask section, means at the ends of the flask section and pattern plate to guide the flask section when it is placed on the pattern plate and to prevent relative longitudinal displacement and lateral displacement at the ends thereof; means on the opposite sides of the pattern plate presenting wedge-receiving faces; co-acting wedge-receiving faces on the flask section; and wedges adapted to be inserted between said faces to hold the intermediate portions of the flask section against lateral displacement, the flask-engaging faces of said wedges affording guides for the

rammed flask section when it is lifted from the match plate whereby to prevent "ratting".

14. Apparatus for molding long castings comprising, in combination, a pattern plate; a flask section adapted to be placed on the pattern plate; said flask section having two plane vertical surfaces on opposite sides intermediate the ends; said pattern plate having two surfaces outside of and opposed to the aforesaid surfaces provided on the flask section which are slightly closed at the tops and at one end to the aforesaid surfaces on the flask section; and wedges which taper both longitudinally and laterally adapted to be driven in between the two opposed surfaces on opposite sides of the flask, the thinner end of each wedge being inwardly and the thicker longitudinal edge of each wedge being lowermost when the wedges are in position; the wedges thus being self-tightening when the apparatus is subjected to jolt ramming.

In testimony that I claim the foregoing as my own, I have hereto affixed my signature.
